APPARATUS FOR FURNISHING AUDIBLE INFORMATION

Andrew R. Johnson, Chicago, and Charles E. Watson, La Grange, Ill., assignors to Informat, Inc., Chicago, Ill., a corporation of Illinois

Application June 15, 1938, Serial No. 213,798

12 Claims. (Cl. 274—18)

This invention relates to information devices and more particularly to a multiple recording selector device for installation in public places and operable to supply audible talk-back on diverse matters of interest from an advertising and information service standpoint, although it may be employed with equal advantage for other purposes.

It contemplates more especially a novel combination of multiple recordings combined with a talk-back selector in a self-contained unit to supply information and various advertising features depending upon the demands and requirements of commercial practice.

It is a familiar fact that travellers and newcomers arriving in municipalities or public places frequently experience difficulty and delay in securing necessary and desired information. Often, residents or people who are well informed are not available or convenient to approach and the newcomer is apt to be misdirected and suffer embarrassment or delay. Further, a person arriving in a strange locality at a late hour may find places of information closed and neighborhoods deserted so that it is often very difficult to acquire information.

Then, too, effective advertising can be acquired by informing individuals through a mechanical record-reproducer unit that is selective, amusing and effective in communicating information and advertising messages. It is proposed therefore, to provide self-contained information machines in depots, public places, and prominent street intersections for contemplated operation day and night to impart spoken information and advertising concerning hotels, streets, office buildings, and other subjects of public interest to persons soliciting such information.

One object of the present invention is to provide a talk-back selector in combination with multiple recordings for the purpose set forth.

Another object of the invention is to provide novel means for issuing the desired information and advertising features in spoken form.

Still another object is to provide multiple pre-formed records in a self-contained device suitably indexed for selective response through a reproducer.

A further object of the invention is to provide an audible mechanical information device with control means for the selection of the desired message reproduction.

A still further object of the invention is to provide a device of the character mentioned which is simple, dependable and capable of a wide vari-

ation in operation for advertising and information service.

Still a further object is to provide a multiple reproducer capable of being readily varied from time to time for announcing selected information and/or advertising responsive to the proper indexing cooperation between one of a multiple series of records and the reproducer.

Other objects and advantages will appear from the following description of an illustrative embodiment of the present invention.

In the drawings:

Figure 1 is a side view in elevation of a device embodying features of the present invention, parts thereof being broken away to clarify the showing. 15

Figure 2 is a front view in elevation of the device shown in Figure 1.

Figure 3 is an enlarged fragmentary front view of a casing showing the indexing device and the informational data mounted to cooperate therewith. 20

Figure 4 is a fragmentary perspective view of the indexing element utilized to retain the informational medium and constituting a portion of the cabinet front. 25

Figure 30 is a sectional view taken substantially along line XXX—XXX of Figure 28.

Figure 31 is a perspective view of a reproducer bracket.

Figure 32 is a perspective view of a pick-up element of the reproducer for confinement in the handle shown in Figure 31.

Figure 33 is a plan view of the reproducer.

Figure 34 is a schematic wiring diagram showing the electrical circuit for operating the various electrical elements such as a motor, reproducer, amplifier, and loud speaker.

The structure selected for illustration comprises a base 10 of any suitable configuration and construction that may be cast or otherwise shaped to serve as an ornamental standard of any height. The base 10 has an upwardly extending structural frame work extension 11 which serves to support a superposed frame 12 that is somewhat wider than the base extension frame work 11, to define an outline for a substantially rectangular casing 13. The casing 13 terminates upwardly, in this instance, in a series of pyramided frusto-conical turrets 14, 15 and 16 to define any desired ornamental and visual effect which may be varied within a wide range to meet the dictates of commercial practice.

As shown, the casing 13 extends downwardly in a converging apron 17 that merges with the upper edge of the base 10 to define an impressive casing for instrumentalities to be hereinafter described. The casing 13 has its front and rear walls 18 and 19, respectively, provided with substantially rectangular openings 20 that comprise the greater part of the wall surface to accommodate an informational device capable of variation to correspond with records confined within the casing 13. To this end, each of the openings 20 in the front and rear walls 18 and 19 are provided with a plurality of transverse bars 21—22, in this instance totalling confronting sets of five which are equi-distantly spaced to define a corresponding number of separate informational

areas 23 that are independent of each other and correspond with separate self-contained instrumentalities numbering in this instance a total of ten units on both sides as will appear more fully hereinafter. The number of units and records 5 therein and the capacity of each unit casing 13 may be varied within a wide range and depends largely upon the requirements as well as the size thereof.

It is to be noted that the transverse sets of 10 bars 21—22 are spaced to present transverse slots or openings 24 therebetween (Figure 6) to permit the vertical displacement within the limits thereof of a control handle 25 that terminates externally in a grip member 26. The upper edge 15 of the transverse plate members 22 are provided with downwardly extending horizontally spaced teeth 27 that accommodate the handle control shank 25 therebetween so as to index such in vertical alignment with the spaces between vertically 20 upstanding struts 28 that are anchored in confronting guide members 29. As shown, the confronting guide members 29 (Figure 6) are substantially U-shaped and are attached to the transverse plate members 21—22 so as to receive 25 the struts 28 therein, the struts 28 having their upper extremities 30 detachably connected between side plates 32 by means of threaded stud screws 32' (Figures 22 and 25) while the lower extremities 31 are soldered, welded or otherwise 30 anchored in channels 33 to define a unitary frame casing section 23 which may be assembled and dismantled by removal of the fastener studs 32'; however, there is sufficient freedom of movement so as to enable the entire section 23 with their 35 studs 28 and indicia blocks 36' to be slidably removed in a horizontal direction.

As shown, the lower side plates 33 terminate in an extension 33' which has a perforated offset ear 34 (Figure 22) disposed in registry with a corresponding frame member 34' (Figure 30) to receive a fastener bolt 35 therebetween in order to retain the assembled section 23 in position against removal from the casing 13. As shown, the struts 28 are provided with longitudinally 45 extending grooves 36 formed on both lateral or side walls thereof so as to confront the corresponding grooves in the adjacent struts 28 to retain indicia or letter blocks 36' therebetween. In order to remove the informational sections 23 and 50 to enable the quick change therein, an entire panel section 23 can be laterally removed from the casing 13 and the top side plates 32 disengaged to permit different indicia blocks 36' to be inserted.

The indicia or letter blocks 36' are slidably received between the confronting vertical grooves 36 provided in the struts 28 so as to define any vertical word or informational indicia for use by the public in indexing the handle member 26 of 60 the control 25 to conform with any special series of letter blocks 36' that will be disposed in vertical alignment between the teeth 27 constituting an indexing member for each of the informational areas or sections 23. The indicia or letter blocks 36' may be composed of translucent Bakelite or other composition so as to emanate light 65 therethrough from a source of illumination such as an electric bulb 37 mounted behind the casing 13 (Figure 6). This provides the adjustable informational areas or sections 23 so as to be readily changed to conform with changes made in the records that are disposed therein for audible informational projection in a manner to be hereinafter described.

It is preferable though not essential that the side walls 38 and 39 (Figure 28) of the casing 13 be rendered removable so that each self-contained operating unit for each informational section will be readily removable for repair, replacement, or record changing. For that matter, each front informational section 23 may be rendered removable for a similar purpose depending upon the dictates of commercial practice. To this end, each of the informational sections 23 are provided with separate and independent instrumentalities such as cross members 40 to bridge the frame 12, the cross members 40 being spaced to conform substantially with the transverse bars 21 of each section 23 so as to support confronting angle irons 41 and 42 disposed normally to the cross members 40 (Figures 6 and 28).

It is worthy of note that there are two parallel sets of confronting angle irons 41 and 42 (Figure 28) that are spaced from each other by vertical beam members 43 disposed intermediate the casing 13 between the slots 18 and 19 thereof so that the front and rear openings 20 can accommodate separate and independently operating units, thereby doubling the capacity of each casing 13 which will be disposed upon its base 10 in an exposed position so that all sides are accessible. Each section 23 is provided with a unit which, in each instance comprises a base 44 sized to be received between the confronting angle irons 41—42 (Figure 6), the base 44 being provided with oppositely disposed notches 45 and 46 in the ends thereof (Figure 8) to accommodate mounting screw bolts 46 so as to fix the base 44 in position and render such readily removable should occasion require for replacement or repair purposes.

In the present embodiment, the base 44 is provided with two end confronting brackets 47 and 48 to support the instrumentalities as will presently appear. To this end, the brackets 47—48 are provided with two horizontally aligned suitable supporting bearings 49 and 50. The bearing 49 receives a stub shaft 51 therein that has a groove oilway 52 and is held fixed by a set screw 53 (Figure 8) to retain such in position. The stub shaft 51 has an adjusting stud 54 that is threadedly connected with a bearing 49 to carry a disc 55 which is in registry with the transverse slots 56 provided near the extremity of the stub shaft 51 (Figure 19), thereby enabling the adjustment of the stub shaft 51 and its retention in position by a set screw 53.

The stub shaft 51 terminates in a conical extremity 57 to cooperate with a correspondingly shaped recess 58 provided in the end of the extremity of an arbor shaft 59 that extends through and is journalled in the other bearing 50. The shaft 59 has a pulley 60 secured to the extremity thereof that extends beyond the bearing 50, the pulley 60 being connected thereto for rotation therewith by means of a key 61 (Figure 19). A comparatively larger pulley 62 having a reduced hub 63 is fixed to the shaft 59 on the inward side of the bearing 50 for attachment, it being secured thereto for rotation therewith by means of a set screw 64.

An arbor or record holder 65 is fixed to the shaft 59, it comprising end hubs 66 and 67 that receive a cylindrical member 68 therebetween for positioning on parallel reduced peripheries 69 and 70 constituting part of the end hubs 66 and 67, respectively. Threaded studs 71 secure the cylindrical member 68 to the end hubs 66 and 67 and the latter are secured for rotation with the

shaft 59 by virtue of set screw 72. A record indexing plate 73 is extended edgewise in a radial direction to project beyond the periphery of the cylindrical member 68 so as to serve as a guide for a plurality of cylindrical records 74 which are disposed in axial alignment with a slot 75 therein to cooperate with the indexing plate 73 so as to insure the correct positioning of each cylindrical record 74 as well as to insure the rotation thereof with the arbor 65.

Each of the records 74 have recording grooves 76 (hill and dale) provided thereon and their end surfaces 77 and 78 are correspondingly tapered so as to insure the proper placement of each record 74 in the corresponding direction on the arbor 65 so that the recordings 76 thereon will be in the right direction. Any number of individual records 74 may be provided on the arbor 65, and in this instance as many as forty to fifty records are axially aligned for adjacent contact in assembly and association on the arbor 65 for retention by means of an end collar member 79 which is internally threaded as at 80 to engage the correspondingly threaded shoulder of the end hub 66. This will serve to retain the records 74 in assembled axial association and enable their ready replacement. Should commercial practice dictate, the individual records 74 may be substituted by a single unitary record having a multiple of individual recordings 76 thereon of uniform length. This constitutes the full equivalent of the individual records 74, one arrangement being the full equivalent of the other and should be so interpreted irrespective of actual descriptive limitations.

It is to be noted that the end bearing 48 is carried by a hanger 81 that has a vertical bearing 82 at one extremity thereof to serve as an element of the furcated lugs 83 and 84 (Figure 9) which are vertically apertured to receive a fastener 85 therethrough for pivoting the bearing hanger 81 together with its bearing 49 in order to detachably associate the stub shaft 51 with the arbor shaft 59 whenever it is desired to change records 74 or otherwise render the arbor 65 accessible. The other extremity of the bearing hanger 81 is provided with another stud 86 which cooperates with a transverse slot 87 provided in the bracket 47 so as to retain the bearing bracket 81 in operative position when the stud 86 is fastened to the bracket 47.

To render the arbor 65 readily accessible for record changing, it is only necessary to detach the stud 86 from engagement with the bracket 47 to enable free swinging of the bearing hanger 81. An electrical reproducer arm 88 is attached to a rod 89 carried between spaced arms 90 and 91 of the bracket 92. To this end, the reproducer arm 88 has a depending portion 93 which is disposed between the arms 90 and 91 of the bracket 92 (Figures 6 and 24) so as to be fixed to the rod 89 by means of a stud screw 94, the rod 89 having a head 95 thereon and a coil spring 96 which normally urges the reproducer arm 88 with its depending portion 93 toward the left (viewed from Figure 24) to the extreme position adjacent the bracket arm 90 while the recordings 76 on the records 74 tend to move the reproducer 88 with its depending portion 93 toward the right and simultaneously compress the spring 96.

The depending portion 93 of the reproducer 88 is journalled on a stub shaft 97 supporting a carriage 98 having upstanding spaced arms 99 and 100 provided with bearings 101 and 102, respectively, which are spaced to receive the

- bracket arms 90—91 therebetween, the latter having corresponding bearings 103 and 104, that are in axial alignment with the bearings 101—102 so as to receive the stub shaft 97 therebetween.
- 5 The carriage 98 in turn is guided for lateral movement by a shaft 105 extending through the bottom bearing 106 provided therein so as to insure movement of the carriage 98 parallel to the arbor shaft 59.
- 10 To this end, the shafts 97 and 105 are disposed and supported between the brackets 47 and 48 of the base 44 so that the reproducer arm 88 together with the bracket 92 and its carriage 98 will have a range of movement within the limits of the arbor 65 and the records 74 disposed thereon. A spring 107 has one of its extremities anchored to the top of the bracket 92 while its other extremity is anchored to a vertical bar 108 (Figure 6) so as to normally urge the reproducer arm 88 in a clockwise direction (viewed from Figure 6) so that its depending portion 93 will be urged against a stop rod 109 having its extremities carried by adjustably mounted plates 110—111 (Figure 24) fixed by screws 110'—111' to the side arms 99—100 (Figure 7) of the carriage 98. The other surface of the depending portion 93 of the reproducer 88 is provided with a block 112 having a sectional threaded bearing opening 113 therein to cooperate with a correspondingly threaded feed rod 114 that also bridges the end brackets 47—48 mounted on the base 44 (Figure 11) for journalled rotation relative thereto responsive to the actuating instrumentalities to be hereinafter described.
- 15 In order to displace the reproducer arm 88 in a counterclockwise direction (viewed from Figure 6), a vertical actuator bar 108 is slidably mounted relative to studs 115—116 that are anchored in the forward wall 117 of the carriage 98 so as to cooperate with slots 118 and 119 provided in the actuator bar 108, the slots 118—119 being of sufficient length to permit the required displacement in order to actuate the reproducer arm 88 to its extreme limits of movement corresponding to its operative and inoperative positions.
- 20 As shown, the upper extremity 120 of the actuator bar 108 is somewhat thinner than the main body thereof to receive a travel guide bracket 121 (Figures 6 and 15) that is fixed thereto by means of a stud fastener 122. The travel guide bracket 121 has a plate 123 fixed to the rearward wall thereof in spaced relation therewith, it being attached thereto by means of studs 124 (Figure 15). The plate 123 has a stepped edge 125 that cooperates with a downwardly offset edge 126 to define the travel of the reproducer 88 which has a lug 127 projecting therefrom for disposition in the path of the stepped edge 125—126 of the travel guide plate 123.
- 25 As a result, when the reproducer lug 127 is disposed on the uppermost edge 125, it is in operative playing relation with the record 74 for such a time as it approaches and descends to the lowermost edge 126 whereupon the reproducer 88 is removed from operative playing position owing to the urge of the spring 107 thereon. Accordingly, the upper travel edge 125 defines the extent of travel for the reproducer 88 while in playing position and thereupon it reaches its extreme limit and is removed from playing operation with the record 74 owing to the descent of the lug 127 to the lower edge 126. When this occurs, the carriage 98 is capable of being returned to its initial inoperative position over the record 74 with which it previously was in engagement owing to the urge

of the spring 96 that displaces the rod 89 carrying with it the reproducer arm 93 that is secured thereto by means of the stud screw 94 (Figure 24).

It should be noted also that the segmental feeding nut 113 is simultaneously disengaged from the rotating feeding screw 114 when the reproducer 88 is displaced in a clockwise direction (viewed from Figure 6) responsive to the urge of the spring 107, thereby enabling the reproducer 88 with its depending arm 93 to be returned to its initial position in disengaged relation with the feed screw 114 that renders the spring 96 free to effect the return of the reproducer 88. It should also be noted that the carriage actuator bar 108 is normally urged downwardly when no particular record 74 has been traversed by the reproducer 88, this being rendered possible by a spring 128 which envelops a rod 129 that is screwed thereto as at 130 into the bottom of the carriage 98 (Figure 6).

To this end, the rod 129 projects through a lug 131 that is adjustably engaged therewith by means of a threaded stud 132 which projects through a slot 133 in the actuator bar 108. The stud 132 engages the lug 131 and projects into engagement with the stud 129 so as to establish a rigid joinder therebetween and cause the coil spring 128 to impart a downward urge to the actuator bar 108 when it is in its extreme elevated position and the release is effected of the locking mechanism that retains it in operative position during the playing contact of the reproducer 88 with the record 74.

The release mechanism that holds the actuator bar 108 in its elevated position during the playing operation, comprises a trip or lever detent 134 (Figure 27) which is pivotally mounted in a horizontal plane as at 135 to the carriage 98 so as to be in the path of a plunger rod 136 having a head 137 impinging thereagainst through the influence and urge of a spring 138 that envelops the plunger rod 136 which is also mounted in the side wall of the carriage 98. As a result, when the actuator bar 108 is elevated to its extreme upper position, a slot 139 (Figure 27) is brought in alignment with the laterally projecting extremity 140 of the pivotal detent 134 so that the spring plunger 136 will cause the engagement of the detent extremity 140 with the slot 139 when it is displaced for registry therewith, thereby holding the actuator bar 108 in its extreme upper position which causes the travel guide plate 123 to depress the reproducer 88 in engagement with the recording grooves on the record 74.

As soon as the reproducer 88 together with its depending arm 93 has traversed the entire recorded extent of the selected record 74, it will contact the detent 134 (Figures 24 and 27) and cause the latter to be displaced against the spring impelled detent 136 and thus dis-engage the detent extremity 140 from the actuator bar slot 139 to allow the spring 127 which envelops the vertical detent 129 (Figure 6) to cause the actuator bar 108 to descend responsive thereto and return such to its initial inoperative position together with the handle control shank 25.

The handle shank 25 terminates in a block 141 (Figure 12). The block 141 is provided with a forward rectangular extension 144 spaced therefrom by means of oppositely disposed grooves 145 and 146 that cooperate with vertical notches 147 spaced along a plate 148 that is fixed to the end bearing brackets 47 and 48 (Figure 11), the notches 147 being spaced to correspond with the

notches 27 on the upper plates 22 so as to co-operate therewith in accurately effecting registry of the reproducer 88 with the starting point on the recording grooves 76 of any selected record 74. To this end, the plate 148 with its notches 147 merely serves as an extra indexing feature to insure correct registry between the starting recording groove of the reproducer 88 which is essential or at least highly desirable.

10 Should there be a blank record 74 on the arbor 65 for any reason, such as the lack of advertising or informational listings thereon, the plate 148 is provided with threaded apertures 149 which are in vertical alignment with the notches 147 so as 15 to receive a plug 150 therethrough, the plug 150 being attached by means of threaded studs 151 that engage any desired threaded apertures 149 so as to close the vertical notch 147 and preclude the actuator bar 108 to be elevated when the handle member 26 has been grasped for displacement over a vacant record 74. Any number of such 20 vacant record plugs 150 may be attached to correspond with the number of records 74 that do not have any informational or advertising recordings thereon.

Now, then, the handle block extension 144 protrudes directly in front of the furcated extremity of the actuator bar 108 that is attached to the forward portion of the grooves 145—146 by 25 means of studs 151 (Figure 6) so as to be elevated responsive to a lifting hand grasp on the handle control member 26. The bar 108 is narrower than the grooves 145—146 so that a portion of the grooves 145—146 on the front of the actuator bar 108 will register with the indexing grooves 147 on the plate 148. Now, then, the reproducer 88 has a full floating cradle 152 which is pivoted as at 153 to one extremity thereof, while the other extremity of the cradle 153 has a carriage bolt 154 extending upwardly therethrough for freedom of movement in an aperture 155 provided on the reproduced body 88.

A spring 156 envelops the bolt 154 and is rendered adjustable by means of a pair of self-locking nuts 157. An electrical pick-up consists, in this instance, of a rectangular body 158 that is shaped for reception in the cradle 152, it being retained therein by means of suitable set screws or studs (not shown) that project through 50 threaded apertures 159 provided in the three side walls of the cradle 152. The pick-up 158 consists of a suitably mounted diaphragm 160, to which a needle or stylus 161 is mounted for vibratory movement in a vertical direction in the path of 55 electrical coils and permanent magnets so as to generate electrical impulses responsive to the stylus 161 serving as a follower in the hill and dale recording grooves 76 indexed on the records 74 to reproduce the message of any selected record 74.

To this end, wires 162 and 163 lead from the reproducer pick-up 158 to a switch that completes the circuit to an amplifier 165. The amplifier 165 is suitably connected to one or more 60 dynamic loud speakers 166 which are mounted, in this instance, in the top inclined portion 14 which is above each of the openings 20 in the front and rear wall of the casing 13, there being suitably perforated grids 167 provided in the upper section of the casing 13 to protect the structure and conceal it from view. The amplifier 165 is preferably supported by the base 10 on the uppermost point thereof (Figure 1) and such is responsive to the handle control 26 on either side of the casing 13 so as to operate one or the other of the

speakers 166 depending upon which side of the casing 13 is being used. For that matter, the amplifier 165 can be provided with separate output channels so that both sides 18—19 of the casing 13 could be used at the same time by different individuals depending upon the information or advertising sought to be reproduced.

Amplifier 165 may have a single input and separate outputs so as to accommodate two reproducers 88 in separate circuits and disposed on opposite sides of the casing 13 or two separate amplifiers 165 may be utilized in separate circuits for that purpose, there only being one circuit schematically shown on Figure 34 to accommodate one side of the casing 13 which has five 15 separate units of which one will only be operated independent of the others.

In order to operate the instrumentalities and effect rotation of the record arbor 65 and simultaneously place one of the pick-ups 158 in the 20 circuit of the amplifier 165 that has its independent switch (not shown), the handle control block 141 has its extension 144 provided with a horizontally disposed ridge 168 which projects into a horizontal slot 169 provided in an angular plate 170 disposed between the end brackets 47 and 48 carried by the base 44 of each unit (Figures 6 and 11). The slotted plate 170 has extensions 171 attached to the extremities thereof to project in vertical slots 172 provided in the end brackets 47 and 48 (Figures 6, 10 and 16). This serves to guide the transverse angle plate 170 so as to be displaced responsive to the handle control 25 in a path parallel to the actuator bar 108 to impart corresponding displacement to a resilient switch actuating springs 173 and 174, in this instance two, that confront detents 175 and 176 (Figure 11) comprising part of the moving parts of micro switches 177 and 178.

The micro switches 177 and 178 are mounted 40 on brackets 179 and 180 which extend to the base 44 so as to maintain such in predetermined spaced relation with the elongated transverse angle bar 170. In consequence thereof, whenever the control handle 25 is displaced upwardly corresponding displacement will be imparted to the transverse bar 170 to close switches 177 and 178 and also the circuit from the reproducer pick-up 158 to the amplifier 165 of the loud speaker 166 as well as simultaneously close the circuit to an 50 electric motor 181, respectively. The motor 181 is mounted on the base 44 of each unit and its armature shaft carries a pinion 182 (Figures 10 and 16) that meshes with a spur gear 183 carried by a stub shaft 184 journalled in a bearing 185 (Figure 21).

The bearing 185 is carried by the end bracket 48 so as to rotatably support the spur gear 183 together with a small belt pulley 186 (Figure 21). The small belt pulley 186 is disposed in alignment 60 with a comparatively larger arbor driver pulley 63 (Figure 19) to receive an endless belt 187 therebetween so as to reduce the speed of rotation between the electric motor 181 and the arbor shaft 59. In order to maintain the endless belt 65 187 in taut condition, an idler roller 188 is journalled on a stud 189 carried by a lever 190. The lever 190 is anchored at one extremity as at 191 to the end bracket 48 while its other extremity is actuated by a spring 192 which tends to urge the 70 idler roller 188 against the endless belt 187 (Figure 16).

As shown, the arbor shaft 59 has a comparatively small pulley 61 on the extremity thereof beyond the bracket 48 (Figure 19) for alignment 75

with the comparatively larger belt pulley 193 fixed to the extremity of the feed screw 114 so as to receive an endless belt 194 therebetween which imparts a substantially slower and substantially decreased rate of rotation thereto to correspond with the best operating characteristics for audible speech reproduction. The endless belt 194 is maintained taut by means of an idler roller 195 mounted on a stud 196 carried by a lever 197 (Figure 10). The lever 197 is pivoted to the bracket 48 as at 198 so as to effect contact between the idler roller 195 and the endless belt 194 through a clockwise urge imparted thereto by a spring 199 (viewed from Figure 10).

15 It will be apparent, therefore, that the energization of the motor 181 by the micro switch 178 will effect the rotation of the records 74 simultaneously with the operative contact of the stylus 161 in starting record groove 76 responsive to elevating the handle control 21. Simultaneously therewith, the reproducer arm 88 is fed along the screw 114 and the circuit is completed through the amplifier 165 and the loud speaker 166 to audibly reproduce and emanate whatever corresponds with the recordings 76 on the selected record 74. When the reproducer 88 with its arm 93 has traversed a predetermined extent of travel corresponding with each recording 76, the reproducer stylus 161 is disengaged from contact and the actuator bar 108 simultaneously descends to its initial inoperative position.

15 The reproducer 88 is then returned to its initial position over the played record 74 and the motor 108 is de-energized simultaneously with the breaking of the circuit between the reproducer 88 and the amplifier 165-loud speaker 166 connections. The amplifier 165 is preferably operating at all times and such can be de-energized at any time by a separate manual switch (not shown) that is rendered accessible on the exterior of the casing 13. It will also be apparent that the record 74 can be changed at will and readily substituted depending upon the requirements and the arrangements thereof. Then, too, 45 the informational sections 23 can be changed by re-arranging and substituting indicia blocks 36' to correspond with the recording 76 on any particular records 74 that may be substituted at any time.

50 Various changes may be made in the embodiment of the invention herein specifically described without departing from any of the advantages of the invention or sacrificing any of the features thereof, and nothing herein shall be construed as limitations upon the invention, its concept, or structural embodiment as to the whole or any part thereof except as defined in the appended claims.

55 We claim:

60 1. In a device of the character described, the combination with a plurality of pre-arranged records, of a sound reproducer mounted to cooperate with said records, means for rotating said records, reciprocable hand control means displaceable 65 normal to the axis of said records for placing said reproducer in operative cooperation with any selected record, a carriage to movably support said sound reproducer along a path parallel to the axis of said pre-arranged records, said reciprocable hand means serving to displace said sound reproducer carriage along the total length of said records, means for limiting the feeding of said sound reproducer for the recorded extent of each record within the total limit of carriage displacement, and means for indexing said recip-

75 roitable handle control means to cooperate with a selected record for the entire recorded extent thereof.

2. In a device of the character described, the combination with a plurality of pre-arranged records, of a sound reproducer mounted to cooperate with said records, means for rotating said records, reciprocable hand control means displaceable normal to the axis of said records for placing said reproducer in operative cooperation with any selected record, a carriage to movably support said sound reproducer along a path parallel to the axis of said pre-arranged records, said reciprocable hand means serving to displace said sound reproducer carriage along the total length of said records, means for indexing said control means to cooperate with a selected record for the entire recorded extent thereof, means for limiting the feeding of said sound reproducer for the recorded extent of each record within the total limit of carriage displacement, and means for returning said reproducer to its initial position on the selected record for further selective record cooperation. 10

25 3. In a device of the character described, the combination with a plurality of pre-arranged records, of a sound reproducer mounted to cooperate with said records, means for rotating said records, each of said records having a plurality of self-contained section recordings thereon in predetermined sequence, reciprocable hand control means displaceable normal to the axis of said records for placing said reproducer in operative cooperation with any selected sectional recording on each record, a carriage to movably support said sound reproducer along a path parallel to the axis of said pre-arranged records, said reciprocable hand means serving to displace said sound reproducer carriage along the total length of said records, means for limiting the feeding of said sound reproducer for the recorded extent of each record within the total limit of carriage displacement, and means including a series of adjacently disposed notches for indexing said control means 30 therein to cooperate with a selected sectional recording on each record for the entire recorded extent thereof. 35

4. In a device of the character described, the combination with a plurality of pre-arranged records, of a sound reproducer mounted to cooperate with said records, means for rotating said records, each of said records having a plurality of self-contained section recordings thereon in predetermined sequence, reciprocable hand control means displaceable normal to the axis of said records for placing said reproducer in operative cooperation with any selected sectional recording on each record, a carriage to movably support said sound reproducer along a path parallel to the axis of said pre-arranged records, said reciprocable hand means serving to displace said sound reproducer carriage along the total length of said records, means including adjacently disposed notches for indexing said control means 40 therein to cooperate with a selected sectional recording on each record for the entire recorded extent thereof. 45

5. In a device of the character described, the combination with a plurality of pre-arranged records, of a sound reproducer mounted to cooperate 50

- with said records, means for rotating said records, each of said records having a plurality of self-contained section recordings thereon in predetermined sequence, reciprocable hand control means 5 displaceable normal to the axis of said records for placing said reproducer in operative cooperation with any selected sectional recording on each record, a carriage to movably support said sound reproducer along a path parallel to the 10 axis of said pre-arranged records, said reciprocable handle means serving to displace said sound reproducer carriage along the total length of said records; means including adjacently disposed notches for indexing said control means to 15 cooperate with a selected sectional recording on each record for the entire recorded extent thereof, means for limiting the feeding of said sound reproducer for the recorded extent of each record within the total limit of carriage displacement, 20 and spring means for returning said reproducer to its initial sectional record position responsive to withdrawing said reproducer from record playing position for further selective record cooperation.
- 25 6. In a device of the character described, the combination with a plurality of pre-arranged records, of a sound reproducer mounted to cooperate with said records, means for rotating said records, each of said records having a plurality of self-contained section recordings thereon in predetermined sequence, means for normally holding said reproducer in spaced inoperative relation relative to said records, reciprocable hand control means displaceable normal to the axis of said records 30 for placing said reproducer in operative cooperation with any selected sectional recording on each record, a carriage to movably support said reproducer along a path parallel to the axis of said pre-arranged records, said reciprocal handle 35 means serving to displace said sound reproducer along the total length of said records, means including adjacently disposed notches for indexing said control means to cooperate with a selected sectional recording on each record for the entire recorded extent thereof, means for limiting the feeding of said sound reproducer for the recorded extent of each record within the total limit of carriage displacement, 40 and spring means for returning said reproducer to its initial sectional record position responsive to withdrawing said reproducer from record playing position for further selective record cooperation.
- 45 7. In a device of the character described, the combination with a casing, of a plurality of pre-arranged records in said casing, a sound reproducer mounted to cooperate with said records, power means for rotating said records, each of said records having a plurality of self-contained section recordings thereon, said records being 50 arranged in predetermined sequence, externally accessible control means projecting from said casing for placing said reproducer in operative cooperation with said records, means including notches in said casing for indexing said control 55 means to cooperate with a selected recording on said records for the entire recorded extent thereof, means for limiting the feeding of said sound reproducer for the recorded extent of each record within the total limit of carriage displacement, and means independent of said control 60 means for elevating and returning said reproducer to its initial sectional record position after traversing the entire sectional recording.
- 65 8. In a device of the character described, the combination with a casing, of a plurality of ax- 70 ily disposed cylindrical records in said casing, a sound reproducer pivotally mounted to cooperate with said records, power means for rotating said records, each of said records having a plurality of self-contained section recordings thereon, said records being arranged in predetermined sequence, externally accessible control means projecting from said casing for placing said reproducer in operative cooperation with said records, means including notches in said casing for indexing said control means to cooperate with a selected recording on said records for the entire recorded extent thereof, means for limiting the feeding of said sound reproducer for the recorded extent of each record within the total limit of carriage displacement, and means independent of said control means for elevating and returning said reproducer to its initial sectional record position after traversing the entire sectional recording.
- 75 9. In a device of the character described, the combination with a rotatable arbor, of a plurality of cylindrical records disposed in axial alignment on said arbor, said records having uniform external cylindrical surfaces in smooth surface alignment, each of said records having interengaging ends to render said records complementary to each other, means on said arbor to retain said records in aligned relation for rotation therewith, a reproducer mounted to cooperate with said records within the limits of said arbor, means for linearly feeding said reproducer longitudinally of said records in timed relation to the recordings thereon responsive to the rotation of said arbor, and means for limiting the feeding of said sound reproducer for the recorded extent of each record within the total limit of carriage displacement.
- 80 10. In a device of the character described, the combination with a rotatable arbor, of a plurality of cylindrical records disposed in axial alignment on said arbor, said records having uniform external cylindrical surfaces in smooth surface alignment, each of said records having interengaging ends to render said records complementary to each other, means on said arbor to retain said records in aligned relation for rotation therewith, a reproducer mounted to cooperate with said records within the limits of said arbor, means for linearly feeding said reproducer 85 longitudinally of said records in timed relation to the recordings thereon responsive to the rotation of said arbor, means for limiting the feeding of said sound reproducer for the recorded extent of each record within the total limit of carriage displacement, and control means for simultaneously initiating the operation of said arbor, feeding means, and reproducer.
- 90 11. In a device of the character described, the combination with a rotatable arbor, of a plurality of cylindrical records disposed in axial alignment on said arbor, said records having uniform external cylindrical surfaces in smooth surface alignment, each of said records having interengaging ends to render said records complementary to each other, means on said arbor to retain said records in aligned relation for rotation therewith, a reproducer mounted to cooperate with said records within the limits of said arbor, means for linearly feeding said reproducer 95 longitudinally of said records in timed relation to the recordings thereon responsive to the rotation of said arbor, control means for simultaneously initiating the operation of said arbor, feeding means, and reproducer, means for limiting the 100

feeding of said sound reproducer for the recorded extent of each record within the total limit of carriage displacement, and means for rendering said arbor, feeding means, and reproducer inactive when said reproducer has travelled the recorded extent of any selected record.

12. In a device of the character described, the combination with a rotatable arbor, of a plurality of cylindrical records disposed in axial alignment on said arbor, each of said records having inter-engaging ends to render said records complementary to each other, means on said arbor to retain said records in aligned relation for rotation therewith, a reproducer mounted to cooperate with said records within the limits of said arbor, means for linearly feeding said reproducer longitudinally of said records in timed relation to the

recordings thereon responsive to the rotation of said arbor, control means for simultaneously initiating the operation of said arbor, feeding means, and reproducer, means for limiting the feeding of said sound reproducer for the recorded extent of each record within the total limit of carriage displacement, means for rendering said arbor, feeding means, and reproducer inactive when said reproducer has travelled the recorded extent of any selected record, and means for returning said reproducer and control means to their initial position when said arbor, feeding means, and reproducer has been rendered inactive.

ANDREW R. JOHNSON.
